UNITED STATES PATENT OFFICE.

LEON L. BLUM, OF CHICAGO, ILLINOIS.

SALT AND PEPPER SHAKER.

1,085,660.

Specification of Letters Patent.

Patented Feb. 3, 1914.

Application filed June 19, 1913. Serial No. 774,534.

To all whom it may concern:

Be it known that I, LEON L. BLUM, a citizen of the United States, and a resident of the city of Chicago, county of Cook, and 5 State of Illinois, have invented certain new and useful Improvements in Salt and Pepper Shakers, of which the following is a specification.

My invention relates to improvements in 10 salt and pepper shakers and has for its object the production of a device of this character which will be adapted to accommodate both salt and pepper and from which either may be discharged at the option of the user.

15 A further object is the production of a device as mentioned which will be simple of construction and neat and finished in appearance.

Other objects will appear hereinafter.

20 The invention consists in the combinations and arrangements of parts hereinafter described and claimed.

The invention will be best understood by reference to the accompanying drawing 25 forming a part of this specification and in which,

Figure 1 is a perspective view of a salt and pepper shaker embodying my invention, the closure of the device being shown 30 removed, Fig. 2 is a bottom plan view of the closure, Fig. 3 is a top plan view of the body of the device, and Fig. 4 is a central longitudinal section of the shaker taken on substantially line $x-x$ of Fig. 3, showing 35 the device in a position for discharging one of the contents thereof.

The preferred form of construction as 40 illustrated in the drawing comprises a cylindrical hollow body 1 formed preferably of glass or other suitable material which is open at its upper end. The interior of the body 1 is divided by a medial longitudinally extending partition 2 into two compartments 3 and 3' adapted for the reception respectively of salt and pepper or other granulated spices or material which it is desired 45 to accommodate. Said open end of said body is closed by a circular closure 4 which is removably secured to said body through 50 conventional bayonet joints, said closure being provided with inwardly extending diametric pins 5 which are adapted for engagement with angular slots 6 provided in the upper end of said body, as will be readily 55 understood.

Provided in the closure 4 are two sets or

lines of discharge openings 7 and 7' inclined or angularly disposed, as clearly shown in Figs. 2 and 4, the inner ends of said passages being adapted, when the closure 4 is in operative position, to register with the outer edge of said partition, as clearly shown in Fig. 4. Said edge of said partition is provided at its opposite sides with substantially V-shaped recesses 8 and 8' 60 adapted respectively for registration with the inner ends of passages 7 and 7', the bottoms of said recesses being inclined to correspond with the angular disposition of said passages, as clearly shown in Fig. 4. With the arrangement set forth, it will be seen, 65 that the recesses 7 will communicate with the compartment 3 and the recesses 7' with the compartment 3', the under side of the closure 4 engaging snugly against the corresponding edge of the partition 2, when said closure is in operative position, to insure a tight connection and prevent the commingling of the contents of the two compartments. 70

In using the shaker the same is held in the hand with the lines of discharge passages or openings horizontally disposed, the shaker being then inclined, as shown in Fig. 4. Upon such inclination it will be seen 75 that the contents of the compartment 3 or 3' which is positioned uppermost will slide or shift downwardly upon the upper side of the partition 2 and discharge through the corresponding discharge openings which 80 will lead downwardly therefrom, as clearly shown in Fig. 4. The contents of the other or lowermost of said compartments will correspondingly shift upon the upper surface of the lateral wall of the body 1. The discharge openings which communicate with 85 said compartment, being positioned at the upper side thereof, or adjacent the partition 2, the contents of the last mentioned compartment will not be brought in registration 90 therewith and hence will be prevented from discharging from the shaker, being retained therein as clearly shown in Fig. 4. Said discharge from the last mentioned compartment is further prevented by reason of the 95 upward inclination of the discharge openings communicating therewith, the contents of said compartment in order to discharge therefrom being, with this disposition of the discharge openings, required to pass upwardly in order to discharge from said passages. Thus, in using the device the same 100 105 110

will be so held as to position the compartment containing the element which it is desired to discharge at the upper side of the shaker. In order to effect the discharge of the other element or of the contents of the other compartment it is obvious that the shaker needs only to be reversed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A shaker of the class described comprising a hollow body; and a substantially medially disposed longitudinally extending partition in said body dividing the interior thereof into two independent compartments, one end of said body having two sets of discharge openings arranged adjacent said partition and leading angularly therefrom, each of said sets of openings communicating with one of said compartments, substantially as described.

2. A shaker of the class described comprising a hollow body; and a substantially medially disposed longitudinally extending partition in said body dividing the interior thereof into two independent compartments, one end of said body having two sets of discharge passages arranged adjacent said partition, each of said sets of passages communicating with one of said compartments, the end of said partition adjacent said discharge passages being recessed at its opposite sides for registration with the inner ends of said passages, substantially as described.

3. A shaker of the class described comprising a hollow body; and a substantially medially disposed longitudinally extending partition in said body dividing the interior thereof into two independent compartments, one end of said body having two sets of discharge passages arranged adjacent said partition and leading angularly therefrom, each of said sets of passages communicating with one of said compartments, the end of said partition adjacent said discharge passages being recessed at its opposite sides

for registration with the inner ends of said passages, the bottoms of said recesses being inclined to correspond with the angular disposition of said passages, substantially as described.

4. A shaker of the class described comprising a hollow body open at one end; a substantially medially disposed longitudinally extending partition in said body dividing the interior thereof into two independent compartments, the outer edge of said partition terminating at said end of said body; and a removable closure for said end of said body adapted, when in operative position, to engage against said edge of said partition to form a tight connection, said closure being provided with two sets of discharge passages so arranged that, when said closure is in operative position, the inner ends of said passages will terminate in registration with said edge of said partition, said passages leading angularly from said partition, said edge of said partition being recessed to establish communication between the inner ends of said passages and said compartment, substantially as described.

5. A shaker of the class described comprising a hollow body open at one end; a substantially medially disposed longitudinally extending partition in said body dividing the interior thereof into two independent compartments, the outer edge of said partition terminating at said end of said body; and a removable closure for said end of said body adapted, when in operative position, to engage against said edge of said partition to form a tight connection, said closure being provided with two sets of discharge passages so arranged that, when said closure is in operative position, the inner ends of said passages will terminate in registration with said edge of said partition, said passages leading angularly from said partition, said edge of said partition being recessed to establish communication between the inner ends of said passages and said compartment, the bottoms of said recesses being inclined to correspond with the angular disposition of said passages, substantially as described.

In testimony whereof I have signed my name to this specification in the presence of two subscribing witnesses.
